UNITED STATES PATENT OFFICE.

FRANCIS GUSTINE, OF MEDFORD, MASSACHUSETTS.

VANE-GOVERNOR FOR STEAM-ENGINES, &c.

Specification of Letters Patent No. 17,623, dated June 23, 1857.

To all whom it may concern:

Be it known that I, FRANCIS GUSTINE, of Medford, in the county of Middlesex and State of Massachusetts, have invented certain new and useful Improvements in Regulators for Cut-Off Valves of Steam-Engines, of which the following is a full, clear, and exact description, reference being had to the accompanying drawings, making part 10 of this specification, in which—

Figures 1 and 2 are front elevations; Fig. 3, an elevation at right angles to the above; Fig. 4, a plan.

In the said drawings A is a pillar or stand 15 through which passes a rod B which is caused to turn in the pillar by any suitable connection from the engine applied to its lower end at a. To this rod near its top is secured the cross piece C which is carried around by the rotation of the rod. From this cross piece rise 20 the standards b in which turn the arms D. These arms are prevented from moving endwise by the enlarged portion c between two of the standards. To the outer end of each 25 arm is attached a metallic disk E which when the governor is at rest as in Fig. 1 hangs down vertically. At the inner end of each arm D is a toe e set at right angles to the disk E, the

toe on one arm pointing in a direction opposite to that on the other. Over the upper 30 end of the rod B is slipped a sleeve F. A pin f passes through the rod and slides in slots g in the sleeve, allowing the sleeve to rise and fall on the rod while it is carried around with it. By the vertical motion of this sleeve the 35 closing of the valve is regulated.

The operation is as follows: As the speed of the engine increases the bar C and with it the disks E are revolved more rapidly and the resistance of the atmosphere against the 40 surface of the disks causes them to be thrown back as in Figs 2, 3, and 4, turning the arms D and raising the toes e which lift the sleeve F. As the speed decreases the disks fall toward the vertical position of Fig. 1 and the 45 sleeve F is lowered.

What I claim as my invention and desire to secure by Letters Patent is—

The disks or vanes E operating directly upon the valve rod toes as described, whereby the valve is actuated by the varying deflections of the vanes as set forth.

FRANCIS GUSTINE.
